HOOK AND EYE HOLDER

Filed Dec. 31, 1930

INVENTOR
Peter Kelley

BY HIS ATTORNEY

H. G. Manning

UNITED STATES PATENT OFFICE

PETER KELLEY, OF WINSTED, CONNECTICUT

HOOK AND EYE HOLDER

Application filed December 31, 1930. Serial No. 505,949.

This invention relates to portable holding devices, and more particularly to a holder for the hooks, eyes and loops employed as dress fasteners.

5 One object of the invention is to provide a holder of the above nature which is adapted to detachably contain a plurality of dress fastener units, each consisting of a hook having an eye and a loop suspended therein.

10 A further object is to provide a holder of the above nature consisting of a pair of parallel strip members carrying a row of fastener units therebetween, the eyes and loops of said fastener units being located beneath

15 said strips, and the eye sections of said hooks being located above said strip in such a manner as to lock said units in position and to prevent the removal thereof except at the open end of said holder.

20 A further object is to provide a detachable holder of the above nature in which the fastener units may be readily removed by the use of only one hand of the user without destroying or otherwise injuring the holder as was formerly necessary when removing fasteners of this nature from cards and previous holding devices.

25 A further object is to provide a holder for fastener units in which the expense of assembling the hooks and eyes therein is greatly reduced.

30 A further object is to provide a fastener unit holder of the above nature, which will be simple in construction, inexpensive to manufacture, easy to fill with fastener units, very efficient and durable in use, ornamental in appearance, and in which the units may be held therein in a compact manner for facilitating the storage, transportation and display of the same.

35 With these and other objects in view, there have been illustrated on the accompanying drawing, two forms in which the invention may be conveniently embodied in practice.

In the drawing:

Fig. 1 represents a perspective view on an enlarged scale of a hook and eye holder of the "straight" type, showing one end section 40 thereof completely filled and closed, and the

other end section partially filled and in open position.

Fig. 2 is a perspective view of the holder showing the parts thereof in separated relation, prior to assembly. 55

Fig. 3 is a view of an assembled fastener unit comprising a hook, an eye, and an "invisible" loop.

Fig. 4 is a plan view of a modified form 60 of hook and eye holder constructed in U-shape, showing one side of said holder completely filled and closed, and the other side partially filled and open.

Fig. 5 is a front elevation of the same.

Fig. 6 is a transverse sectional view taken 65 along the line 6—6 of Fig. 4.

Figs. 7, 8, and 9 are front views of a hook, a U-shaped eye, and a straight "invisible" loop respectively.

Referring now to the drawing in which 70 like reference numerals denote corresponding parts throughout the several views, the numerals 10 and 11 indicate a pair of parallel strips which will hereinafter be termed the "back strip" and "front strip" respectively, and between which the rows of fastener units, generally indicated by the numeral 12, are adapted to be detachably carried. Each of the fastener units 12 is made up of a wire hook 13 having upper eyes 13a, 80 a U-shaped wire eye 14 and an "invisible" wire loop 15, said parts being shown separately in Figs. 7, 8, and 9 respectively, and assembled in Fig. 3. 75

The back strip 10 is provided at its ends 85 with a pair of inwardly offset outwardly curved resilient end tongues 16 and 17, which are adapted to cooperate with a similar pair of inwardly offset outwardly curved resilient end tongues 18 and 19 formed on the front 90 strip 11. The tongues 16 and 17 are adapted to align with the tongues 18 and 19 and to contact therewith lightly for facilitating the insertion and removal of the assembled fastener units 12 through the openings 20 and 95 21.

In order to press the row of fastener units 12 constantly toward the front strip 11 of each receiving chamber 21a of the holder, provision is made of an elongated spring 100

strip 22 having a straight central section 23, said spring strip 22 being provided with forwardly curved extremities 24 and 25 terminating just short of the offset tongues 16, 17, 18 and 19.

To connect the front and back strips 10 and 11 and lock the spring strip 22 therebetween, the central portion of the front strip 11 is provided with a rearwardly offset section 26 spaced from the front of said strip 11 by a distance slightly greater than the width of the fastener units.

The offset section 26 is adapted to lie in contact with the central section 23 of the spring strip 22 and is securely held to the back strip 10 by a pair of side lugs 27 and 28 extending forwardly from the central portion of said back strip 10 and adapted to be bent around said spring strip 22 and offset section 26, as clearly shown in Fig. 1.

The bent-over side lugs 27 and 28 at the center of the hook and eye holder may be covered, if desired, by a paper strip, not shown, having any suitable ornamental or advertising matter. The pairs of resilient tongues, 16, 18 and 17, 19 at the ends of the holder may be similarly covered by detachable paper loops 29 and 30 which serve to hold said tongues in contact and prevent the accidental loss of any of the fastener units during storage or shipment.

The modified form of the U-shaped holder shown in Fig. 4 is similar with the first form of the invention except that the end sections 31 and 32 thereof are bent in the same direction and lie at right angles to the central section 33 thereof. This produces a dress fastener holder of about one-half the length of the first form.

40

Operation

When it is desired to fill the holder with fastener units 12, it will merely be necessary for the operator to hold said units parallel to the plane of the front and back strips 10 and 11 and pass them inwardly between the cooperating end tongues. The units may then be twisted 90 degrees to the position shown in Figs. 1, 4 and 5, being thereafter held in this position by the pressure of the curved extremities 24 and 25 of the spring clip 22.

When the receiving chambers have been completely filled, the ends of the tongues 16 and 18, 17 and 19 may be detachably locked together in contacting engagement by the locking loops 29 and 30.

To remove the fastener units from the holder, the locking loops 29 and 30 will first be taken off, thereby opening the ends of the holder, whereupon the endmost fastener units may be readily moved manually out of the receiving chambers in a longitudinal direction, past the end of the spring strip 22 and

out between the inwardly offset end tongues 16, 18, and 17, 19.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a holder for a plurality of dress fastener units, each comprising an assembled hook, eye, and loop, a pair of connected parallel spaced strips of sheet metal for receiving said units in a row, each unit lying at right-angles to the plane of said strips, and inwardly offset means on the ends of said strips for closing the ends of said strips to prevent accidental removal of said units.

2. In a holder for a plurality of dress fastener units each comprising an assembled hook, eye, and loop, a pair of connected parallel spaced outwardly pressed strips of sheet metal for receiving a row of said units, each unit lying at right-angles to the plane of said strips, said strips having inwardly offset ends, and loop means for detachably locking the ends of said strips together.

3. In a holder for a plurality of dress fastener units, each comprising an assembled hook, eye, and loop, a pair of connected parallel outwardly pressed resilient spaced strips for receiving a row of said units, each unit lying at right-angles to the plane of said strips, and loop means for detachably locking the ends of said strips together, each of said strips having offset inwardly extending end tongues for contacting each other when said loop means is in position.

4. In a holder for a plurality of dress fastener units each comprising an assembled hook, eye, and loop, a pair of connected parallel resilient spaced normally divergent strips for receiving a row of said units, each unit lying at right-angles to the plane of said strips, loop means for detachably locking the ends of said strips together, and means for permanently joining the center of said strips to provide a pair of end chambers for receiving two sets of said fastener units, whereby said units may be assembled and removed from both ends of said holder.

5. In a holder for a plurality of dress fastener units each comprising an assembled hook, eye, and loop, a pair of connected parallel spaced strips for receiving a row of said units, each unit lying at right-angles to the plane of said strips, loop means for detachably locking the ends of said strips

together, and means for permanently pointing the center of said strips to provide a pair of end chambers for receiving two sets of said fastener units, the end of said holder being bent in the same direction to produce a **6** U-shape holder.

6. In a holder for a plurality of dress fastener units, each comprising an assembled hook, eye, and loop, a pair of connected parallel spaced strips for receiving a row of said units, each unit lying at right-angles to the plane of said strips, loop means for detachably locking the ends of said strips together, each of said strips having offset inwardly **10** extending end tongues for contacting with the ends of the other strip, and a spring strip located between said spaced strips to hold said units in position even though one of said spaced strips is flexed outwardly.
7. In a holder for a plurality of dress fastener units, each comprising an assembled hook, eye, and loop, a pair of connected parallel spaced strips for receiving a row of said units, each unit lying at right-angles to **15** the plane of said strips, loop means for detachably locking the ends of said strips together, each of said strips having offset inwardly extending end tongues for contacting with the ends of the other strip, and a spring strip the ends of which terminate short of said offset tongues located between **20** said spaced strips to hold said units in position even though one of said spaced strips is flexed outwardly.
8. In a holder for a row of dress fastener units, each of which comprises an assembled hook, eye, and loop, a back strip having inwardly offset tongues at its opposite ends, and a pair of intermediate forwardly extending lugs, a front strip having inwardly offset tongues adapted to engage the corresponding tongues on said back strip and having an intermediate offset section in alignment with said lugs, a spring strip lying between **25** said back and front strips, said lugs being bent over around said spring strip and front strip for locking said parts together.
9. In a holder for a plurality of dress fastener units, each comprising an assembled hook, eye, and resilient normally loop, a pair of resilient normally diverging spaced strips of strip metal for receiving said units in a row, means for connecting said strips at a point between their ends, each unit lying at **30** right-angles to the plane of said strips, and means for connecting the ends of said strips to lock said units within said holder.

In testimony whereof, I have affixed my signature to this specification.

60 PETER KELLEY.

CERTIFICATE OF CORRECTION.

Patent No. 1,865,112.

June 28, 1932.

PETER KELLEY.

It is hereby certified that error appears in the printed specification of the above numbered patent requiring correction as follows: Page 3, line 1, claim 5, for the syllable "point-" read join-, and line 4, for "end" read ends; same page, line 50, claim 9, strike out the words "resilient normally"; and that the said Letters Patent should be read with these corrections therein that the same may conform to the record of the case in the Patent Office.

Signed and sealed this 4th day of October, A. D. 1932.

**M. J. Moore,
Acting Commissioner of Patents.**
